CENTERING DEVICE

Walter E. Frisk, Chicago, Ill., assignor to Montgomery Ward & Co., Incorporated, Chicago, Ill., a corporation of Illinois

Application August 27, 1949, Serial No. 112,817

5 Claims. (Cl. 33—191)

1

This invention relates to a centering device for use in commercial establishments engaged in engraving a large amount of table cutlery.

Heretofore the procedure followed for engraving such cutlery by an engraving machine was for the operator, through his experience and skill, to approximate the centerline of the handle before applying the engraved design thereto. This procedure was time consuming and also resulted in a variance in the location of the design on the handle. The more elaborate the design, the more difficult it was for the operator to correctly position the engraving.

Thus, it is one of the objects of this invention to provide a device which will enable the operator to quickly determine the centerline of the handle and thus expedite the engraving operation.

It is a further object of this invention to provide a device which is adapted to accommodate cutlery of various sizes and shapes.

It is a still further object of this invention to provide a device which is simple in construction, effective in operation, and inexpensive to produce.

Further and additional objects will appear from the description, accompanying drawings, and appended claims.

In accordance with one embodiment of this invention, a device is provided for finding the longitudinal centerline of the handle of a piece of table cutlery comprising a base having an element slidably mounted thereon. Pivotedly connected to the upper end of the slidable element is a pair of self-aligning gripping members. The element is adapted to normally assume a retracted position and the gripping members, a gripping relationship. A means is mounted on the base for actuating the element in a vertical direction whereupon the gripping members assume a non-gripping relationship. Mounted on the base is a bracket having a portion thereof extending above and over the gripping members. A punch is slidably mounted on the extended bracket portion and is positioned in superposed relation with respect to the slidable element.

For a more complete understanding of this invention, reference should be made to the drawings wherein

Fig. 1 is a fragmentary side elevational view 50 of the device.

Fig. 2 is a fragmentary vertical section of the device shown in Fig. 1.

Fig. 3 is a fragmentary perspective view of the overhanging portion of the bracket.

2

Fig. 4 is a plan view of the device taken along line 4—4 of Fig. 1.

Fig. 5 is a perspective view of one of the gripping members.

5 Fig. 6 is a fragmentary top plan view of the pivotal connection for the gripping members.

Referring now to the drawings and, more particularly, to Figs. 1 and 2, a centering device 10 is shown comprising a base 11 shown in the form of a block, and a post 12 slidably mounted within a suitable opening 13 formed within said block. The post 12 is actuated in a vertical direction by means of an operating lever 14, which is pivotally connected at point 15 to the block 11. The enclosed end 16 of lever 14 is positioned within a notch 17 formed in the periphery of the post 12. The exposed or opposite end 17' of lever 14 is shaped into a suitable handle 18. The operating lever is adapted to normally hold the post 12 in a retracted position by means of a coil spring 19 which is secured at one end to block 11 and, at the other end, to a lug 19' laterally mounted on the exposed end portion 17' of said lever. A suitable opening 20 is formed in block 11 so as to enable the lever 14 to move about pivot point 15.

To the upper end of post 12 is pivotally connected at point 21 a pair of gripping members or jaws 22 and 23. The gripping members are adapted when the shaft is moved upwardly by lever 14 to assume a non-gripping relationship. Suitable guides or rests 24 and 25 are mounted within a cavity 25', formed in the upper portion of block 11 and positioned on either side of post 12, so as to engage and cause the gripping members 22 and 23 to assume a gripping position when the post is retracted within the opening 13.

Mounted on the side of block 11, opposite from the side on which operating lever 14 is mounted, and extending upwardly therefrom is a bracket 26 having the free end 27 thereof laterally offset and disposed above and over gripping members 22 and 23. Mounted on portion 27 of bracket 26 is a bushing 28 in which is slidably mounted a punch or marking device 30 having the lower end 31 thereof pointed and case-hardened. The operation of the punch 30 will be discussed more fully later.

Gripping members 22 and 23 are of like construction, comprising pedestal members 32 and 32a, and jaw members 35 and 35a, respectively, adjustably mounted thereon. The lower end 33 of pedestal member 32 is bifurcated and is 55 adapted to receive a tongue formed in end 33a

of pedestal member 32a as shown in Fig. 6. Ends 33 and 33a are embraced by and pivotally mounted on the bifurcated upper end 39 of post 12. The upper portions 34 and 34a of the pedestal members 32 and 32a, respectively, are enlarged and substantially flat and serve to support the jaw members mounted thereon. The jaw members are secured to portions 34 and 34a of the pedestal members by means of shouldered holding bolts 36 and 36a, respectively, which extend through suitable openings 37 formed in the jaw members 35 and 35a and are threaded into the corresponding pedestal members. The shouldered shank 37' of each bolt prevents the jaw member from being drawn up tightly against the supporting surface of the pedestal member. Thus, each jaw member is adapted to move relative to the pedestal member. A small amount of clearance 38 is provided in each jaw member between the shouldered shank 37' and the periphery of opening 37. Pins 40 and 40a, positioned parallel to and spaced from bolts 36 and 36a, extend through suitable openings formed in the jaw members. The ends of pins terminate within the respective pedestal members. The jaw members 35 and 35a are self-aligning and adapted to pivot about pins 40 and 40a, respectively. The amount of movement of the jaw member about the pin is dependent upon the clearance 38 hereinbefore mentioned.

The opposing or cooperating surfaces 41 and 41a of the jaw members 35 and 35a, respectively, are serrated as shown in Figs. 1, 2, and 5. The corresponding serrations formed in the jaw members are of various sizes so as to accommodate the handle portions of table cutlery of varying designs, shapes, and sizes.

Prior to the cutlery being engraved by the engraving machine, the handle 42 of the cutlery is positioned within the appropriate pair of serrations formed in the gripping members 22 and 23. To permit insertion of the handle 42 between the gripping members, the operator presses down on the exposed handle 42 of lever 14, thereby causing the post 12 to be moved upwardly and the members 22 and 23 to spread apart. After the handle 42 has been correctly positioned between the gripping members, the operator releases the lever 14, and the spring 19 forces said members into gripping relation with respect to the handle. As seen in Fig. 4, the jaw members are adapted to align themselves with respect to the periphery of the handle 42 to be more firmly gripped therebetween. After the handle 42 has been positioned, as shown in Fig. 4, the operator presses down on the punch 30 causing an indentation or mark to be made on the handle by the pointed tip 31 of the punch. The punch is normally held in its up or inoperative position by a coil spring 43, which embraces the upper portion of the shank. One end of the spring 43 engages the upper end of bushing 28 and the other end an enlarged head 44 formed at the upper end of the punch.

The free end portion 27 of bracket 26, see Fig. 3, is provided with an opening 45 to permit a screw driver to be inserted therethrough into engagement with the holding bolt 36 of the gripping member 23 for adjustment thereof. One side of the end of portion 27 is cut away slightly, as shown in Fig. 3, so as to enable the operator to more readily view the work positioned between the gripping members.

Thus, it will be seen that a centering device

has been provided which greatly facilitates the operator in performing the engraving operation. Furthermore, the device eliminates guesswork on the part of the operator in determining the correct location of the engraved design on the handle.

While a particular embodiment of this invention is shown above, it will be understood, of course, that the invention is not to be limited thereto, since many modifications may be made and it is contemplated, therefore, by the appended claims, to cover any such modifications as fall within the true spirit and scope of this invention.

15 I claim:

1. A device of the class described comprising a block having an opening formed therein, an elongated element slidably mounted within said opening, work-gripping jaws pivotally mounted 20 on said element and adapted to be actuated from a normally gripping relation to a temporary non-gripping relation upon slidable movement of said element, means pivotally mounted on said block for effecting slidable movement of 25 said element, a bracket mounted on said block and having a portion thereof extending above and over said jaws, and a marking device slidably mounted on said extended bracket portion and having the axis of said marking device centered between the adjacent surfaces of said gripping members.

2. A device of the class described comprising a base, an elongated vertically extending post mounted on said base for longitudinal movement and adapted to normally assume a down position with respect to said base, a pair of self-aligning work-gripping members operatively connected with the upper end portion of said post, guides mounted on said base and arranged 35 on either side of said post and adapted to engage said jaws and effect movement of said jaws toward each other when said post is in said down position, means pivotally mounted on said base for actuating said post to an up position and effect movement of said jaws away from each other, and a marking device mounted on said base for movement in a line centrally positioned with respect to the opposing surfaces of said jaws.

3. A device of the class described comprising a base, an element mounted for reciprocatory movement on said base and adapted to normally assume a position at one terminal of its reciprocatory movement, a pair of work-gripping jaws adjustably connected with said element and adapted to assume a gripping relation when said element is at said one terminal position, means pivotally mounted on said base for actuating said element from said terminal position to a position whereby said jaws assume a non-gripping relation, and a work-marking device mounted on said base for movement in a line centrally positioned with respect to said jaws.

6. A device of the class described comprising a base, a post mounted for reciprocatory movement on said base and adapted to normally assume a position at one terminal of its reciprocatory movement, a pair of pedestal members pivotally mounted on one end of said post, a work-gripping jaw element adjustably mounted on each of said pedestal members, guides mounted on said base and disposed on opposite sides of said post and adapted when said post 70 is at said terminal position to engage said pedestal members.

estal members and effect closing together of said pedestal members, means pivotally mounted on said base for moving said post from said terminal position to a position whereby said pedestal members assume an open relationship with respect to one another, and a marking device mounted on said base for movement in a line coincident to the axis of said post for marking a work piece held between said jaw elements.

5. A device of the class described comprising a block having an opening formed therein, a post slidably mounted within said opening, a pair of pedestal members pivotally connected with one end of said post, a pair of jaw elements, one of said jaw elements swivelly mounted on each of said pedestal members, a post-actuating lever pivotally mounted on said block and having one end thereof engaging said post and having the other end thereof extending outwardly from said block, said lever, adapted to normally assume a rest position, whereby said post is retracted within said opening and said

pedestal members assume a relatively closed position with respect to one another.
